DESIGN FOR A WALL RACK OR SIMILAR
ARTICLE

Louis Lonstein, Bronx, N. Y.

Application April 16, 1946, Serial No. 128,637

Term of patent 3½ years

(Cl. D33—3)

To all whom it may concern:

Be it known that I, Louis Lonstein, a citizen of the United States and resident of the Bronx, in the county of Bronx and State of New York, have invented a new, original, and ornamental Design for a Wall Rack or Similar Article, of which the following is a specification, reference being had to the accompanying drawing, forming a part thereof, and of which Fig. 1 is a perspective view in front elevation of a wall rack or similar article showing my new design; Fig. 2 is a view in rear elevation; and Fig. 3 is a sectional view taken on line 3—3 of Fig. 1.

I claim:

The ornamental design for a wall rack or similar article, substantially as shown.

LOUIS LONSTEIN.
